COMBINED BUCKLE AND LIGHTER

Albert W. Paciello, Richmond Hill, N. Y.

Application October 17, 1951, Serial No. 16,998

Term of patent 3½ years

(Cl. D48—27)

To all whom it may concern:

Be it known that I, Albert W. Paciello, a citizen of the United States of America, residing in Richmond Hill, county of Queens, and State of New York, have invented a new, original, and ornamental Design for a Combined Buckle and Lighter, of which the following is a specification, reference being had to the accompanying drawing, forming part thereof, wherein,

Figure 1 is a front perspective view of a combined buckle and lighter, showing my new design in locked position.

Figure 2 is a rear elevational view of same.

Figure 3 is a view similar to Figure 1, showing the buckle and lighter in semi-separated position.

Figure 4 is a front perspective view of the buckle and lighter in separated positions, and showing the lighter open.

Figure 5 is a rear elevational view of the lighter in closed position.

I claim:

The ornamental design for a combined buckle and lighter, substantially as shown.

ALBERT W. PACIELLO.
